(57) **CLAIM**

The ornamental design for a gear shift stick, as shown and described.

DESCRIPTION

FIG. 1 is a perspective view of a gear shift stick, showing the design;

FIG. 2 is a right side view thereof, the left side view being a mirror image thereof; and,

FIG. 3 is a front view thereof.

The broken lines shown in the drawings depict portions of the gear shift stick that form no part of the claimed design.
